(57) **CLAIM**

The ornamental design for a vegetable spray, as shown and described.

DESCRIPTION

FIG. 1 is a front perspective view of the vegetable spray showing my new design;

FIG. 2 is a rear perspective view thereof;

FIG. 3 is a left side elevational view thereof;

FIG. 4 is a rear elevational view thereof;

FIG. 5 is a top plan view thereof;

FIG. 6 is a front elevational view thereof;

FIG. 7 is a bottom plan view thereof; and,

FIG. 8 is a right side elevational view thereof.

The broken line showings of the activation button in FIGS. 1–5, 7 and 8, of the base in FIGS. 1–8, and of the internal annular shoulders are for purposes of illustration only and form no part of the claimed design.
